UNITED STATES PATENT OFFICE.

WILLIAM S. HADAWAY, JR., OF NEW YORK, N. Y.

ELECTRIC HEATER.

4,101,072.

Specification of Letters Patent. Patented June 23, 1914.

Application filed August 16, 1911. Serial No. 644,467.

To all whom it may concern:

Be it known that I, WILLIAM S. HADAWAY, Jr., a citizen of the United States, residing at New York, in the county of New York and State of New York, have invented new and useful Improvements in Electric Heaters, of which the following is a full, clear, concise, and exact description, reference being had to the accompanying drawings, forming a part of this specification.

My invention relates to electric heaters.

For the purposes of illustration, I shall in this application describe my invention as applied to a matrix drier, such as is used in printing, to dry the paper matrix from which the printing form is cast. My invention is not however, limited either to this particular form or to the particular use herein described for purposes of illustration, but may assume other forms and be used in other relations.

It has heretofore been proposed to provide matrix driers, wherein the matrix is dried by the heat generated from gas. In such devices, however, the gas has been used to generate pressure. Due to the types of castings which are usually employed in such service it has been necessary to hold down this pressure. Consequently the temperature to which the device has been capable of being heated has been correspondingly held down, the temperature being dependent upon the pressure. Accordingly the heating operation has been retarded. In rush work, such as that incident to the issue of an extra edition of a newspaper the loss of a single minute between the time the type is set and that when the paper is upon the street is exceedingly expensive. Consequently this defect of the gas heated matrix drying tables is an exceedingly serious one. Further, in such devices the matrix is apt to become soiled from the soot or dirt necessarily attendant upon the use of gas. In order to obviate some of the defects incident to the use of gas, it has been proposed to use steam-heated tables, but in such tables the temperature obtained is dependent upon the pressure, and consequently, a sufficiently high temperature to produce a sharp, clear matrix is not obtainable without the use of an excessive and dangerous pressure, and the use of an unnecessarily heavy equipment.

My invention has, among its objects, to provide an improved electric heater, capable

of being run at a high temperature and of producing a clearer, more sharp matrix in a shorter time than it has been possible to do heretofore.

A further object of my invention, is to provide an electrically heated matrix drier, wherein the heat is evenly distributed over the bed of the drier and delivered directly to the same.

A further object of my invention is to provide an improved, inexpensive, simple and reliable matrix drier which is absolutely safe in operation, wherein the temperature of the drying bed may be graduated to any predetermined degree and automatically maintained at that temperature despite all variations in the temperature of the matrices placed upon the bed, without the necessity for the attention of the operator.

Other objects and advantages of my improved construction will hereinafter appear.

In the accompanying drawings, I have illustrated one form which my invention may assume in practice. My invention is not, however, limited to this specific form, but may assume other forms.

In the views of these drawings:—Figure 1 shows a side elevation of the complete machine. Fig. 2 shows an end elevation of the same. Fig. 3 shows the control panels in elevation. Fig. 4 shows a top plan view of the bed plate, with portions of the same broken away. Fig. 5 shows a sectional view on line 5—5 of Fig. 4. Fig. 6 shows one of the heating elements for the bed plate. Fig. 7 shows a section of one form of resistance material. Fig. 8 shows a diagram of the circuit connections for the device.

In these drawings I have illustrated a matrix drying press of the usual form. The electrically heated bed plate 1, hereinafter described, occupies the usual position upon the top of the frame 2. Over this bed plate is an upper press member 3, and beneath the plate 1, suitable means, such as a cylinder 4, are provided for supplying pressure to the press from a suitable source of pressure supply. The admission of pressure to this cylinder may be controlled by a lever 5, mounted under the forward edge of the apron 6, and connected to the cylinder by suitable piping. At the front of the press and beneath this apron 6, are located the control panels of the device. As in the usual construction suitable ejecting mecha-

nism for throwing the matrix forward upon the bed plate for removal may be provided, such as the ejecting member 7, operable through the link 8 and the foot lever 9 at 5 the front of the press. If desired, the upper press member 3, may be adjusted by a hand-wheel 10.

The bed plate 1, in which the heating elements are inclosed, is shown in Figs. 4 10 and 5. As illustrated in these figures, this bed plate comprises two parts, 11 and 12 preferably formed of cast metal, and bolted together by suitable bolts 13. The upper plate 11 is provided with a comparatively 15 thick top plate and with longitudinally extending ribs 14, which serve to divide the inner portions of the plate into a plurality of chambers. As illustrated in Fig. 5, the lower plate 12 is also provided with similar 20 ribs 15, which are adapted to unite with the ribs 14 to form between the plates a series of closed chambers of rectangular cross-section. Both of these plates are provided with ribs or flanges, 16, around the edges of their 25 adjacent faces, so that when bolted together they form a closed casing. Within the chambers between these plates are inclosed the heating elements for the device. In a preferred form these heating elements are 30 in the form of blocks of heat absorptive material in which a resistance material is secured in suitable manner. In a preferred form these heating elements are of the construction shown in Fig. 6, wherein is illustrated a long block of soap-stone 17, having 35 a plurality of longitudinally extending saw cuts 18 in its surfaces, in which are laid lengths of resistance material 19, preferably of the reflexed wire type. A suitable insulating filler may be placed in the cuts if desired. In a preferred form, I divide up the 40 saw cuts on these blocks into sections, five saw cuts being provided on each side, and two sets of five saw cuts each being provided upon the top and bottom of each block. As illustrated in Fig. 4, I may use 45 six blocks. When reflexed resistance wire is laid in these saw cuts it may be more tightly compressed upon the top of the device and near its ends, as well as upon the sides, where 50 the sides are adjacent to the sides of the bed, since the heat is more rapidly dissipated from these parts. Consequently to maintain 55 a uniform temperature over the surface of the entire device it is necessary to supply more heat to these parts. In a preferred form, the resistance of the several blocks which go to make up the heater is, for the same reason, also graduated from the sides 60 toward the center, the blocks on the sides having the lesser resistance, while those toward the center have greater resistance. The lower plate 12 is preferably provided with transversely extending ribs 20, which serve 65 to position the heating elements within the

chambers and hold them close against the inner surface of the plate 11. A length of the pipe or tubing 21, is so arranged with respect to the plate 11, as to be substantially integral with it, so that the heat imparted to the plate is directly conducted to the tubing. In a preferred form, this tubing 21 is made of steel and arranged in convolutions cast in the metal of the plate 11 slightly below the upper surface of the same, so that portions of the tubing extend over substantially the entire surface of the plate. This is clearly shown in Fig. 4. One end of this tubing 21 is suitably sealed and the tubing is partially filled with a liquid, the pressure of which 70 when heated is a direct function of the temperature. In a preferred form, I use water as this liquid. In order to close the tubing, I may provide one end of the same which extends out of the bed plate with a suitable 75 pet-cock 23. A suitable funnel 24 may also be provided, so that more liquid may be supplied when needed. It is, however, unnecessary to replenish this water except at rare intervals, since both ends of the tubing 80 are closed and the water has no means of escape. The other end of the tubing 21 is connected through a suitable pipe 25 with a pressure gage 26, preferably mounted on a panel 27, supported between standards 28 at 85 the front of the press and beneath the apron 90 6. If desired, the connection of the pipe 25 to the pressure gage may be made by brazing, in order to secure a tight joint.

The pressure gage 26, may be of any desired construction, and is provided with the usual indicating needle 29. In my improved construction, however, contacts 30 and 31 are provided, which are adjustably mounted, preferably upon the dial of the pressure gage, as for instance, upon rings 32 and 33. These contacts are adapted to be engaged by the needle 29 of the pressure gage, and are so connected that when the pressure reaches predetermined points electric circuit 100 controlling devices are operated to cut in or out of circuit the heating units in the bed plate. By the provision of the adjustable contacts 30 and 31, it is evident that the device may be made to operate between any 105 predetermined pressures.

In Fig. 8 I have diagrammatically illustrated a preferred form of circuit connections for the controlling devices, these devices being connected to a line 34-35, and the whole device being adapted to be cut in or out of circuit by a suitable line switch 36. In this figure, I have only shown the resistance r^1 to r^6 , inclusive, of one of the heating elements connected in circuit. As 110 illustrated these resistances are diagrammatically shown connected to terminal blocks 37 on a panel board; the resistances r^1 , r^2 and r^4 , r^5 , which represent the resistance elements laid in each of the ten saw 115 120 125 130 135

cuts on the top and bottom of the block, being connected in parallel and placed in series with resistances r^3 , r^6 , representing the resistance material in the five saw cuts 5 on each side of the block. It is, of course, obvious that the resistance material in the other heating elements may be connected in the same manner as those herein shown. As heretofore described, the needle 29 of the 10 pressure gage 26 is adapted to make or break the circuit connections for these resistances at either of its extreme positions, in order to cut the heating device in or out of circuit. When either of these contacts 15 30, 31, is engaged, an automatic switch 38 of any suitable type, preferably operated by a solenoid, is actuated, and the electrical connections of the heating elements are either made or broken. In order to provide means 20 for dividing up the resistance of the heating elements so that intermediate heats may be provided, I employ a plurality of suitable switches, 39, 40 and 41, which are connected in the separate circuits of the top, side and 25 bottom resistances, as indicated on the drawing.

In a preferred form, these switches are of the knife-switch type, and are carried on a panel 42, located between the standards 30 28 and above the panel 27 at the front of the press. As shown in the diagram in Fig. 8, the switch 39, controls the resistance in the slots or saw cuts upon the tops of the heating elements, the switch 40 controls the resistance upon the sides of the heating elements, and the switch 41 controls the resistance upon the bottoms of the same. Thus 35 it is seen that I am able to graduate the heat to any desired amount and at the same time 40 provide automatic means for cutting the heating devices in or out of circuit within any predetermined limits.

In order to provide suitable factors of safety, suitable fuses 43 may be placed in 45 circuit with the switches 39, 40 and 41, and larger fuses 44 may be placed in the main circuit. In a preferred form, these fuses are mounted on the panel 42, adjacent to the switches 39, 40 and 41. As an additional 50 safe-guard, I have also provided a heavy fuse 45, located in the circuit of the magnetic switch 38 and preferably at the back of the bed, which is adapted to melt at a pre-determined high temperature, to open the 55 circuit of the magnetic switch and thus prevent damage to the device from the over-heating of the bed, if for any reason the temperature should reach this point.

By the use of my improved construction, 60 I have provided an electric heater, wherein the temperature is evenly distributed over the surface of the bed and wherein this bed may be brought to its maximum temperature within a very short time. Further, by 65 the provision of my improved means for

regulating this temperature, wherein the tubing is formed in the bed plate, the pressure of the liquid within the tubing is a direct function of the temperature of the bed plate. Further, by the arrangement of the 70 tubing in convolutions in the bed plate, I am able to obtain an integrated temperature over the whole surface of the same. By the use of the pressure actuated regulator I am able to provide an exceedingly simple 75 and rugged construction, wherein a minute change in temperature produces a wide variation in pressure, so that the device may be very closely regulated. By the provision of the independently adjustable contacts 80 upon the pressure regulator, I am able to govern the closeness of the regulation by moving the contacts toward and away from each other, as well as adjust the temperature zone in which the regulation is effected. 85 Further, by the provision of the independent switches for the several circuits of the heating elements I am able to graduate the heat supply from the heater to any desired amount. The adjustment of the heating elements in this way closely co-operates with 90 the adjustments which are effected on the regulator and make the device operate automatically to cut the heat elements in or out within any predetermined limits. Fur- 95 ther by the provision of my improved controlling mechanism, I am able to provide a simple controlling system by which the heater is cut in or out of circuit automatically without the necessity for the attention 100 of the operator. Further, by the provision of the various safety devices, such as fuses, which are located in the various circuits and the improved manner in which I inclose 105 the resistance elements, I am able to provide an exceedingly safe device. Further, by the provision of my improved heater and its controlling mechanism, I am able to provide a heater which may be brought to its maxi- 110

time than has been possible with the devices heretofore known. In addition, I find that a matrix dried with my improved heater is more sharp and clear than the matrices dried by the gas driers. Further, with my im- 115 proved heater no difficulty is experienced from the soiling of the matrix by soot, etc. Further, by my improved heater construction, I have provided a heater which is adapted to readily absorb the heat trans- 120 mitted to it and retain this heat, so that it may be readily and quickly transmitted to a cold matrix when the same is placed upon the bed. Further, by my improved arrangement of controlling devices, I am able to 125 so locate these devices that they are readily accessible to the operator and yet are not so located as to interfere with the inspection of any of the other parts of the press.

In my co-pending application Serial 130

Number 749,595 filed February 20, 1913, which is a continuation of this application, I have claimed broadly the combined heater and regulator which is set forth herein, the claims of the present application being limited to the specific thermometer circuit breaker system set forth and described.

While I have in this application described one specific form which my invention may assume in practice, I do not wish to be limited thereby as my invention may be embodied in various forms.

What I claim as new and desire to secure by Letters Patent is:—

- 15 1. In a temperature regulator for a heated body, the combination with an electric heater, a supply circuit therefor and means for adjusting the heater to vary the amount of heat generated therein, of electro-responsive means for energizing and deenergizing the heater, a thermometer influenced by the heater, a movable contact actuated by the thermometer and independently adjustable stationary contacts adapted to be engaged by the movable contact at predetermined temperatures, said contacts being adapted to

govern the aforesaid electro-responsive means.

2. In a temperature regulator for a heated body, the combination with an electric 30 heater, a supply circuit therefor, and a plurality of control switches for adjusting the heater to vary the amount of heat generated therein, of a controller for opening and closing the supply circuit, an electro-magnet for 35 actuating the controller, a thermometer influenced by the heater, a movable contact actuated by the thermometer, and independently adjustable stationary contacts adapted to be engaged by the movable contact at pre-determined indicated temperatures, said contacts being adapted to govern the controller for automatically continuing and interrupting the supply of energy to the adjusted heater.

In witness whereof, I have hereunto subscribed my name in the presence of two witnesses.
